UNITED STATES PATENT OFFICE.

ROSCOE C. HOFFMAN, OF ARGOS, INDIANA.

ENGINE.

No. 906,136.

Specification of Letters Patent.

Patented Dec. 8, 1908.

Application filed May 6, 1907. Serial No. 372,212.

To all whom it may concern:

Be it known that I, ROSCOE C. HOFFMAN, a citizen of the United States, residing at Argos, in the county of Marshall and State of Indiana, have invented a new and useful Improvement in Engines, of which the following is a specification.

My invention relates particularly to internal combustion engines; and my primary object is to provide an engine of this character of exceedingly simple construction, in which the vibration and strain are reduced to a minimum, the use of valve-gear and stuffing-boxes obviated, and economy of operation secured.

A further object is to provide a simple engine of the character indicated, for an explosion at each revolution of the crank-shaft and for a desirable uniformity of torque upon the crank-shaft of the engine.

The invention is illustrated in the accompanying drawings, in which—

Figure 1 is a vertical sectional elevation of my improved engine, and Fig. 2 a plan section taken at the line 2 on Fig. 1.

In the construction illustrated, A represents an engine - cylinder, surmounting a crank - casing B, and within the cylinder works a pair of telescopically-arranged pistons A¹, A². A crank-shaft B¹ is journaled in the casing B, and is provided with a pair of cranks B² joined by connecting-rods B³ to the adjacent end of the cylindrical-piston A¹, and a crank B⁴ joined by a connecting rod B⁵ to the inner piston A².

The cylinder A comprises an inner cylindrical wall a and an outer wall a¹ forming a water-jacket as is common in gas-engine construction. The cylindrical piston A¹ is a relatively long piston and has an open end turned toward the crank-shaft and extending normally into the casing B where it is equipped with a ring a² provided with wrist-pins to which the connecting rods B³ are joined. Between the outer end of the cylinder and the adjacent end of the cylindrical-piston A¹ is a chamber a³ provided with an inlet-port a⁴, near the head of the cylinder, and near the opposite, or open end of the cylinder, is a similar inlet-port a⁵ in alignment with the port a⁴, and diametrically opposite the port a⁵ is arranged an exhaust-port a⁶; both the ports a⁵ and a⁶ extend through the inner and outer walls a and a¹ respectively of the cylinder.

Near the head, or outer end of the piston

A¹ is a slot c adapted to register, in the reciprocations of the piston, with the spark-plug c¹ which extends through the cylinder at a boss c² which joins the two walls a, a¹ of the cylinder at this point. The cylindrical piston A¹ is provided with an inlet-port c³ and an exhaust-port c⁴ adapted to register with the ports a⁵ and a⁶ respectively when the piston is in the position shown in Fig. 1 of the drawing.

An inlet-pipe d provided with a branch pipe d¹ and having its upper end turned at a right-angle as shown at d², is secured to the cylinder so that its end d² and branch d¹ will register with the ports a⁴ and a⁵ respectively, and within the inlet pipe, at a point below the branch - pipe d¹ is arranged a check-valve d³.

The piston A² is provided with a deflector d⁴ adapted to direct the explosive mixture toward the outer end of the cylindrical piston A¹ and to prevent the incoming mixture from passing directly to the exhaust-port c⁴.

The operation will be readily understood from the foregoing description. When the crank-shaft is turned through one-half revolution from the position shown in Fig. 1, the outer end of the cylindrical piston A¹ sucks a charge through the valve d³ and port a⁴ into the chamber a³ within the cylinder. When the crank-shaft continuing its revolution, again separates the pistons, the outer end of the cylindrical piston A¹ compresses the charge in the chamber a³ until the port c³ of this piston registers with the intake port a⁵ when the charge enters the cylindrical piston. During the next half revolution of the crank-shaft, the charge is pressed between the pistons, and an instant thereafter it is fired, the slot c being at this time in registration with the spark-plug c¹. Thereupon the pistons are forced apart, the inner piston forcing the crank-shaft in one direction and the sleeve-piston drawing the crank-shaft in the other direction. During the final operation of the separation of the pistons, the port c⁴ is brought into registration with the exhaust-port a⁶ whereupon the burned gases escape through the exhaust-pipe c⁵ leading from the cylinder. Just after the partial opening of the port a⁶ to permit the exhaust to take place, the port c³ is brought into registration with the inlet port a⁵ to permit a fresh charge to enter the piston, as above described, resulting in driving out the burned gases which still remain within the cylinder.

drical piston after the exhaust proper has taken place.

The foregoing detailed description has been given for clearness of understanding only, and no undue limitation is to be understood therefrom.

What I regard as new and desire to secure by Letters Patent, is—

1. In an engine, the combination of a cylinder having one end open and the other closed, said cylinder having a lateral surface provided with two admission ports, one of said ports being located adjacent the closed end of the cylinder and the other between the first port and the open end of the cylinder, a valved inlet pipe connected to both said ports, the valve being located in front of the point of connection with either port, a pair of telescopic-pistons, one of which is hollow and provided with an unobstructed lateral admission - port which passes transversely through a lateral wall of the same and opens into the interior of the hollow piston, thereby serving to admit the charge directly between the pistons, means for exhausting the used charge from between the pistons, and a crank-shaft connected with said pistons.

2. In an engine, the combination of a cylinder having one end open and the other closed, said cylinder having a lateral surface provided with two admission ports, one of said ports being located adjacent the closed end of the cylinder and the other between the first port and the open end of the cylinder, a valved inlet pipe connected to both said ports, the valve being located in front of the point of connection with either port, a pair of telescopic-pistons, one of which is hollow and provided with an unobstructed lateral admission-port which passes trans-

versely through a lateral wall of the same and opens into the interior of the hollow piston, thereby serving to admit the charge directly between the pistons, said cylinder being also provided with an exhaust port located opposite the admission port which is more remote from the closed end of the cylinder, said hollow piston being provided with an exhaust port in line with the admission port, a deflector carried by the head of the other piston, and a crank shaft connected with both said pistons.

3. In an engine, the combination of a cylinder having one end open and the other closed, said cylinder having a lateral surface provided with two admission ports, one of said ports being located adjacent the closed end of the cylinder and the other between the first port and the open end of the cylinder, a valved inlet pipe connected to both said ports, the valve being located in front of the point of connection with either port, a pair of telescopic-pistons, one of which is hollow and provided with an unobstructed lateral admission-port which passes transversely through a lateral wall of the same and opens into the interior of the hollow piston, thereby serving to admit the charge directly between the pistons, a spark plug entered in one side of the cylinder, said hollow piston being provided at one side with an opening adapted to be in registration with said spark plug, means for exhausting the used charge from between the pistons, and a crank-shaft connected with both said pistons.

ROSCOE C. HOFFMAN.

In the presence of—

GEORGE O. REED,
EUGENE E. WILLSEY.
